United States Patent Office

Des. 204,012
Patented Mar. 8, 1966

204,012

PLATE

Viktor Schreckengost, Cleveland, Ohio, assignor to The Salem China Company, Salem, Ohio

Filed Apr. 21, 1965, Ser. No. 84,896

Term of patent 7 years

(Cl. D44—15)

The figure is a plan view of a plate of conventional configuration showing my new design.

I claim:

The ornamental design for a plate, as shown and described.
